UNITED STATES PATENT OFFICE.

CHARLES DREW, OF ST. LOUIS, MISSOURI.

QUARTER-BOOT FOR HORSES.

SPECIFICATION forming part of Letters Patent No. 339,050, dated March 30, 1886.

Application filed May 1, 1885. Serial No. 164,090. (No model.)

To all whom it may concern:

Be it known that I, CHARLES DREW, of the city of St. Louis, in the State of Missouri, have invented a certain new and useful Improvement in Quarter-Boots for Horses, of which the following is a full, clear, and exact description, reference being had to the accompanying drawings, forming part of this specification.

10 Figure 1 is a perspective view of the quarter-boot. Fig. 2 is a side view of the same with part broken out.

A is a sock, of soft leather, formed to envelop the whole of the hoof except the sole.

15 This is open in front and secured at this point by straps and buckles *a a'*. The boot has a piece of harness or other leather, B, which extends around the hind part of the hoof and extends from the lower edge of the hoof to its

20 crest, and which is stitched to the sock A, that forms a lining for piece B.

C C are two pieces of harness or other leather whose under or rear edges are made fast to the upper edge of the piece B, and which are 25 so shaped that when the boot is secured to the hoof pieces C lie snugly upon the quarters of the hoof, the sock of course being interposed between them and forming a lining to them.

D D are re-enforcing strips of leather, which 30 cover the joints between the pieces B and C, and which are stitched in position.

E is a central metal tooth, which is secured to the back part of the boot, and which is formed to rest in the middle crease or recess of the frog, (of the hoof,) so as to hold the boot 35 down upon the hoof. The tooth is shown as secured in position by rivets F and a surrounding line of stitches extending through the layers of leather, between which its upper part is inserted.

I have described the hook E as made of metal, and this is the material I prefer; but any material may be used that would answer the described purpose without essentially changing the principle of construction.

40 I claim—

1. The combination, with a quarter-boot, of the central tooth, E, secured to the rear part of the boot and adapted to fit the frog-recess, substantially as set forth.

45 2. A quarter-boot consisting of a sock, A, a piece, B, pieces C and C, secured to the upper edge of said piece B, re-enforce strips D D, covering the joints between said pieces B and C C, and a central tooth, E, the said tooth 50 55 adapted to fit the frog-recess, substantially as set forth.

CHARLES DREW.
